UNITED STATES PATENT OFFICE.

WIRT HOLMES BROWN, OF SYCAMORE, OHIO.

FENCE-POST.

SPECIFICATION forming part of Letters Patent No. 398,698, dated February 26, 1889.

Application filed May 31, 1888. Serial No. 275,532. (No model.)

To all whom it may concern:

Be it known that I, WIRT HOLMES BROWN, a citizen of the United States, and a resident of Sycamore, in the county of Wyandot and State of Ohio, have invented certain new and useful Improvements in Fence-Posts; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention and is a vertical cross-section through the fence-rails, the anchor-beam being shown above ground. Fig. 2 is a back view and shows the anchor-beam beneath the surface of the ground. Figs. 3 and 4 are horizontal sections.

The invention relates to improvements in fence-posts, adapted more particularly for use in portable fences; and it consists in the construction and novel combination of parts, as hereinafter set forth.

Referring to the drawings, A designates the base or anchor beam, standing transversely to the rails of the fence, and designed, when used in connection with a portable fence, to be placed upon the surface of the ground. In a stationary fence, however, the anchor-beam is firmly embedded in the ground.

B is the fence-post, which consists of a single spring-metal rod bent centrally, as at a, to form the two parallel portions b, having the lower ends firmly seated in the sockets c in the anchor-beam.

It is evident that the anchor-beam may be of iron cast integral with the fence-post.

C designates U-shaped clamping-bolts having threaded ends to engage the nuts d. The clamping-bolts are placed beneath and against

the lapped ends of the fence-rails D, and a fish-plate, E, is interposed between the nuts d and the outer side of one of the portions b of the post. The U-shaped bolt is made long and its span is small, so that its branches are just far enough apart to take in the diameter of the post-rod. It is applied parallel to the plane of the post, so that its bend embraces one branch of the post and its threaded ends extend beyond the other branch for the attachment of the plate E, which bears against said other branch.

The post, being made of metal having a slight spring, is drawn tight and slightly depressed into the wood of the fence-rails by means of the clamping-bolts, thus making a strong and serviceable fence.

Having described my invention, what I claim is—

The portable fence described, consisting of the anchor-base, the elongated centrally-bent rod B, having its branches attached to said base and forming the post, the lapped rails D between the branches of said post, the elongated U-shaped clamp-bolt C, having its branches separated by a narrow interval and extending from the bend around one branch of the post parallel to the plane of the post under the lap of the rails, the perforated plate L, engaging the other branch of the post, and the nuts d, engaging the threaded ends of the clamp-bolt, whereby said ends can be drawn up uniformly and the branches of the post rod braced and caused to become pressed into the wood of the rails, holding them securely, substantially as specified.

In testimony whereof I affix my signature in presence of two witnesses.

WIRT HOLMES BROWN.
